UNITED STATES PATENT OFFICE.

MARTIN LANDENBERGER, JR., OF PHILADELPHIA, PENNSYLVANIA.

DESIGN FOR A CAPE.

Specification forming part of Design No. 6,630, dated May 6, 1873; application filed April 8, 1873.

To all whom it may concern:

Be it known that I, MARTIN LANDENBERGER, Jr., of Philadelphia, Pennsylvania, have invented a Design for a Garment, of which the following is a specification:

In the accompanying drawing, Figure 1 represents a rear view of a circular cloak or garment made in accordance with my design, as it appears upon the wearer, and Fig. 2 represents a skeleton outline of the said garment.

The garment is of a semicircular, or nearly semicircular, shape, and has a hood, A, with slightly curved outlines *a a*, the material of which the hood is composed being so cut and turned over as to present the appearance of lapels *b b*, beneath which is a row of buttons *c*, and at the lower extremity of the hood is a bow, *d*, with long pendent ends, but a tassel

might be substituted for this bow. A deep fringe, *e*, of the character represented extends around the hood and the semicircular outline of the garment, and is also attached to the ends of the bow *d*.

Irrespective of the colors employed, I claim—

1. The design for the hood A, with or without the bow *d*.
2. The design for the whole garment, substantially as described, and as represented in and by the accompanying drawing.

In testimony whereof I have signed my name to this specification in the presence of two subscribing witnesses.

MARTIN LANDENBERGER, JR.

Witnesses:

J. J. BUCHEY,
JNO. JAY WARD.
